[57] CLAIM

The ornamental design for a dental floss container, as shown and described.

DESCRIPTION

FIG. 1 is a top plan view of a dental floss container showing my new design.

FIG. 2 is a front elevational view thereof;

FIG. 3 is a right side elevational view thereof;

FIG. 4 is a bottom plan view thereof;

FIG. 5 is a left side elevational view thereof; and,

FIG. 6 is a rear elevational view thereof;

The broken lines shown in FIGS. 3 and 6 are for illustrative purposes only.
